UNITED STATES PATENT OFFICE.

FREDERIC W. C. SCHNIEWIND, OF NEW YORK, N. Y.

COKE-OVEN AND DOOR THEREFOR.

976,931.

Specification of Letters Patent. Patented Nov. 29, 1910.

Application filed October 24, 1907. Serial No. 398,904.

To all whom it may concern:

Be it known that I, FREDERIC W. C. SCHNIEWIND, a citizen of the United States of America, residing in the city, county, and State of New York, have invented a certain new and useful Improvement in Coke-Ovens and Doors Therefor, of which the following is a true and exact description, reference being had to the accompanying drawings, which form a part thereof.

The present invention relates to the construction and arrangement of the coking retorts or chambers of coking ovens, and particularly to the construction and arrangement of the removable wall portions or doors through which the retorts are charged and discharged.

One object of the present invention is to provide a simple and effective oven door construction so arranged that when necessary it can be readily removed and can be readily put back and sealed in place, and which when sealed in place serves to effectually close the doorway against air or gas leakage and to insulate the coking chamber against heat loss.

A further object of the invention is the provision of a suitable follower which is preferably formed by or connected to one of the doors of the coking retort and which is arranged to bear against the coking body or charge during the coking operation and thereby improve either the coke formed or the volatile products recovered, or preferably to improve both the coke and the volatile components of the coking operation. The follower may improve the coke by compressing the charge during the coking operation and thereby producing a denser and more uniform grade of coke. By serving as a displacing agent the follower may prevent the formation of spaces in the hot portions of the retort in which the volatile products would otherwise collect and stagnate more or less. The "cracking" of the hydrocarbons resulting from their long exposure to high temperatures which is thus avoided results in a material increase in the value of the volatile products recovered in the coking operation.

The various features of novelty which characterize the invention are pointed out with particularity in the claims annexed to and forming a part of this specification. For a better understanding of the invention, however, reference may be had to the

accompanying drawings and descriptive matter in which several forms of the apparatus embodying the invention are illustrated and described.

Of the drawings, Figure 1 is a sectional elevation of a coke oven through a coking chamber having doors at the top and bottom which are of the improved type. Fig. 2 is a section taken at right angles to Fig. 1. Fig. 3 is an elevation of a modified top door construction, and Fig. 4 is a section taken similarly to Fig. 2 showing the modified door of Fig. 3 in place.

In the drawings, and referring first to the constructions shown in Figs. 1 and 2, A represents the fire-brick walls of the coke oven structure, and A' a masonry inclosing shell. The masonry may be supported in any suitable manner, though preferably by the metal floor beams A² and columns A³. In the walls A are formed one or more coking retorts or chambers B, each of which in the form shown is long and deep but narrow. The retorts may be heated in any suitable manner, as by heating flues B' at the sides of the retorts, which may be connected at their upper and lower ends with burner chambers B² and with passages B³ running to regenerative chambers, as described and claimed in application Serial No. 398,902 filed of even date herewith.

The retorts B in the structure shown are charged with coal through their upper ends, and the coke formed is discharged through the lower ends of the retorts. On this account each retort is provided with a removable top wall or door, and a removable bottom wall or door. The top wall or door comprises a body C of heat resisting and insulating material, such as hollow fire-brick, tile, or the like, and a metal cap piece or frame C'. In the form shown, longitudinal grooves C² are formed in the tile in which enter the flanged members C³ of the member C', thus effectually securing the parts together. The member C' is also provided with a depending flange portion C⁴ which enters telescopic fashion the space, groove, or trough formed between the upwardly extending ribs E' formed on the metal rim member E which surrounds the upper end of the retort B. The member C⁴ and the member E and its ribs E' thus unite to form a seal which may be packed with any suitable material.

The top door is provided on its upper

sides with perforated ears C⁵, which may be engaged by suitable operating devices when the door is to be lifted into or out of place.

The bottom door comprises an inner part D which extends to the upper edges of burner chambers B² and may be substantially like the part C, and an under metal supporting part D' on which the part D rests and may be secured by any suitable means as lugs D² of the part D' entering recesses in the tile or brick part D. The bottom door, however, is provided with a flange D³ which with the body of the member D' and the bottom plate D⁴ form the trough into which the flange F' of the rim F projects to form the seal. Each bottom door may be held in place by any suitable means, as for instance by the pinion actuated bolts or rack bars F² sliding in guides F³ to engage and disengage the ends 20 of the yokes F⁴ secured to the under side of the door.

The mechanism for raising and lowering the walls or doors C and D in charging and discharging the retort forms no part of the present invention and for that reason is not illustrated or described herein.

In operation, when the oven is "around", i. e., the coke in it is ready to be discharged, the lower door is removed and the coke formed is discharged in a proper manner; the door is then replaced and the seal completed by inserting the packing material in the space between the ribs D⁵. The upper door is then removed and the charge of coal 35 to be coked is inserted and compacted up to the desired level. After this is done the cover or door is replaced and its seal is completed by the insertion of the packing material between the ribs E'. The height to 40 which the retort is filled will depend on the character of the coal composing the charge. Some coals contract in coking while others expand, the change in bulk depending on the amount of volatile matter in the coal. 45 Coals with less than twenty per cent. of volatile matter expand materially, while coals with thirty to thirty five per cent. of volatile matter shrink very considerably. On this account the retort should be filled 50 with expanding coal to such a height that the expansion will not break the seal by carrying the flange C' above the tops of the ribs E', and with shrinking coal to such a height that the flange C' will not engage 55 the rim member E to thereby hold the weight of the door off the charge.

While by making the ribs C' and E' of suitable height a considerable variation in bulk of the charge cake can be taken care of, 60 with coals which change greatly in bulk such as those containing high amounts of volatile matter where the change in bulk is most marked, the top door construction shown in Figs. 3 and 4 may preferably be 65 employed. In this construction a supple-

mental cap C⁵ is secured to the tile body C, and carries rods C⁶ which pass freely through the cap piece C', and have eyes C' at their upper ends for engagement by the operating devices. With this arrangement 70 the cap piece C' remains stationary while the body C rises or falls with the top of the charge. With this construction as with the bottom door in any case, the telescoping flanges need overlap only enough to form 75 an effective seal. Where the overlapping flanges do not move after the initial adjustment, as is the case with the bottom door and with the top door of Figs. 3 and 4, the seal packing may be formed of any suitable 80 liquid, pulverized material, such as sand or coal dust, lime or clay, or other luting material. Of course, where the overlapping flanges or ribs have relative movement during the coking operation the packing material 85 must be so chosen that the movement will not break the seal. In any event the operation of packing the seals is a simple and inexpensive one. The sealing troughs can be readily cleaned after each seal breaking, and the masonry walls are not injured by the adherence to them of luting material 90 as has frequently been the case with oven door constructions heretofore used.

In the oven shown the volatile products 95 escape to suitable reservoirs or receptacles through the inclined vents B⁶ in the end walls of the retort, the lower vents being protected against clogging by the coal by means of the forebays B⁷. As the cover body 100 C rests on the top of the charge and practically fills the upper end of the retort there is no space in the retort in which the volatile products can collect, consequently as they are given off from the coal they pass at 105 high velocity along the walls of the retort to the escape vents and are not overheated.

As shown, the movable follower portion or body C of the upper wall or door is made of substantial depth or thickness measured 110 in a vertical direction, and in practice I make the vertical dimension of the follower C great enough so that when the retort is properly charged, the upper portion of the body C will be maintained throughout the 115 entire coking operation at a level not below that of the top passages B⁸, so that while some volatile products may accumulate above the body C, such accumulation is well 120 above the hot part of the retort walls which terminates practically with the level of the passages B⁸. The weight of the top door or the follower portion of it should of course be so proportioned as to impress the right pressure on the charge with the consequent 125 avoidance of spongy coke.

In addition to the advantages pointed out above, it will be observed that the doors are mechanically well constructed to serve as the movable walls of a horizontally elongated 130

retort of large capacity which is charged through its upper ends along its entire length and from which the coke formed may be moved out in an unbroken cake.

5. No specific claim is made herein to the special features of construction shown in Figs. 3 and 4, as those features are claimed specifically in my copending application Serial No. 437,042, filed June 6th 1908, as a 10 division of this application.

Having now described my invention, what I claim as new and desire to secure by Letters Patent is:

1. In combination, a coke oven having a 15 coking chamber provided with vents for the escape of the volatile constituents of the charge coked, and means acting automatically as the charge changes in volume to prevent the formation of a space or spaces 20 in the high temperature portion of said chamber in which the volatile constituents can collect and remain stagnant.

2. In combination, a coke oven having a 25 coking chamber provided with vents for the escape of the volatile constituents of the charge coked, and means for preventing the formation of a relatively stagnant body of such volatile constituents in the high temperature portion of said chamber, said 30 means comprising a movable follower held against the surface of the coking body during the coking operation, said follower being of such horizontal and vertical dimensions as to substantially fill the high temperature portion of the upper end of the coking chamber not occupied by the charge 35 being coked.

3. In combination, a coke oven structure having a coking chamber and a movable top

wall for said chamber bearing on the top 40 of the charge during the coking operation and free to move with it as the charge shrinks or expands, said follower being of such dimensions horizontally and vertically as to substantially fill the high temperature 45 portion of the upper end of the coking chamber not occupied by the charge being coked.

4. In combination, a coke oven structure having a coking chamber and a movable top 50 wall for said chamber comprising an outer sealing portion and an inner portion of refractory material which substantially fills the upper end of said retort and bears on the charge and is free to rise or fall with 55 the charge as the latter expands or shrinks during the coking operation.

5. In combination, a coke oven having a coking chamber provided with vents for the escape of the volatile constituents of the 60 charge coked, said vents being formed at different levels in each end wall of the retort, and means for preventing the formation of a relatively stagnant body of such volatile constituents in the high temperature 65 portion of said chamber, said means comprising a movable follower held against the surface of the coking body during the coking operation, said follower being of such horizontal and vertical dimensions as to 70 substantially fill the high temperature portion of the upper end of the coking chamber not occupied by the charge being coked.
